UNITED STATES PATENT OFFICE

JOHN RALPH FEHR, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed December 2, 1926. Serial No. 152,262.

This invention relates to cooling units for mechanical refrigerators, and more particularly to cooling units which are adapted to be installed in refrigerating cabinets of the household type. However, it is to be understood that the present invention may be adapted for larger refrigerating cabinets of the commercial type.

The present invention includes among its objects the provision of a cooling unit of simple and economical construction which will quickly congeal or freeze substances which are placed within a freezing compartment provided by the unit, and which will effectively cool the food compartment of the cabinet.

Further objects and advantages of the present invention will be apparent from the following description, reference being had to the accompanying drawings, wherein a preferred form of the present invention is clearly shown.

In the drawings:

Fig. 1 is a front view of a refrigerator cabinet with the doors open in order to show the food compartment and a cooling unit within a cooling compartment;

Fig. 2 is a view on a larger scale than Fig. 1, showing the front view of the cooling unit which is suspended within the cooling compartment of a cabinet, the walls of which are shown in vertical section; and

Fig. 3 is a side elevation of the cooling unit drawn to the same scale as Fig. 2.

Referring to the drawings, 20 designates a refrigerator cabinet which provides an L-shaped food compartment 21 separated from a cooling compartment 22 by a horizontal partition 23 and a vertical partition 24. The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture, dripping from the cooling unit above, from entering the flue 26. The baffle 27 directs such moisture upon the upper surface of the partition 23, and this moisture is conducted away through a drain pipe 28.

The cooling unit located within the cooling compartment 22, includes a boiler or header 30 attached to the top wall of the cabinet by bracket members 31 and 32. Condensed refrigerant is conducted to the header 30 from a compressor and condenser (not shown) through a pipe 33 and a fitting 34. Refrigerant is admitted from the fitting 34, as needed, by a float-controlled valve (not shown), of suitable construction, located within the header 30. Expanded refrigerant is conducted back to the compressor through a fitting 35 and a pipe 36. The refrigerating compressor and condenser with which the pipes 33 and 36 are connected, may be located outside of the cabinet, if desired, or may be placed within a machine compartment located below the food compartment 21, said compartment having a removable front wall 37 provided with louvers 38.

The cooling unit includes a plurality of ducts 40 and 41 of metal of good thermal conductivity connected with the header 30 at their upper ends and closed at their lower ends. These ducts may be arranged as shown in horizontal rows. The inner rows co-operating with the header to enclose a quick freezing space 42. The ducts 40 are located more remote from the space 42 and are subjected to the currents of air which circulate through the flues 25 and 26. Preferably, the outer rows of ducts 40 are staggered relative to the inner rows of ducts 41 so that the ducts 40 will not over-lie the ducts 41. Thus the air which descends between the ducts 40 may descend freely into contact with the ducts 41. The staggering of the rows of ducts 40 and 41 also permits staggering the rows of holes provided along each side of the header to receive the ducts, thus allowing close spacing of these holes without undue weakening of the side walls of the header. This arrangement also permits a greater quantity of frost to accumulate upon the ducts 41 without substantial obstruction to the flow of air along the ducts 40, than would be the case if the ducts were not staggered in arrangement.

The connections of the ducts with this header are preferably made before attaching and thermally connecting with the ducts

41 one or more metal sleeves 43 for receiving 5 trays 44 containing matter to be frozen or congealed. Since the ducts are independently movable, the ducts 41 can be individually adjusted so that they will conform with and make good contact with the side walls of the sleeves 43 which may be joined thereto by soldering, brazing or the like. Likewise the ducts 40 may be bent relative to the header 30 so that they may be located most advantageously and effectively within this space between the unit and the walls of the cooling compartment. Thus the unit may be adjusted within certain limits to suit cooling compartments varying in size and shape.

In operation, the space 42 becomes colder than other portions of the chamber 22 since this space is somewhat isolated from the air currents passing the ducts by reason of the 20 location of the ducts 41, and for the further reason that the accumulation of frost upon the ducts 41 is greater than upon the ducts 40. The latter condition results from the fact that the ducts 41 remain cold during the idle 25 periods of the refrigerating machine due to their partial isolation from air currents and thermal contact with frozen substances within the space 42, whereas the ducts 40 are warmed by these air currents.

30 If desired, the ducts 40 may be provided with vertical laterally extending fins or plates to increase the cooling effect thereof upon the air coming in contact therewith, thereby either cooling the air to a lower temperature or increasing the air-cooling capacity of the cooling unit, and the proportions and arrangements of the ducts 40 and attached fins may be such that these parts are partially de-frosted during the idle periods 35 of the refrigerating machine or remain partially free from frost thereby further increasing the cooling effect due to the absence of frost which tends to retard the transfer of heat from the air to the metal parts of the 40 cooling unit.

45 While the form of embodiment of the present invention as herein disclosed, constitutes a preferred form, it is to be understood that other forms might be adopted, all coming 50 within the scope of the claims which follow.

What is claimed is as follows:

1. A cooling unit for mechanical refrigeration comprising: an elongated header, and a plurality of ducts depending from the header and closed at their lower ends, certain ducts co-operating directly to enclose a freezing space below the header, and certain other ducts being spaced from the freezing space so as to be completely exposed to air circulating adjacent the cooling unit.

2. A cooling unit according to claim 1 in which the ducts which enclose the freezing space are located in vertical rows on either side of a freezing space below the header.

3. A cooling unit according to claim 1 in

which the ducts are arranged in at least four spaced vertical rows, the inner rows co-operating with the header to enclose a freezing space below the header, and the outer rows being located so as to be completely exposed to air circulating adjacent the cooling unit.

4. A cooling unit according to claim 1 in which the ducts which directly enclose the freezing space support shelves for receiving ice trays.

5. A cooling unit for mechanical refrigerators adapted to be placed in the path of the medium to be cooled thereby, said cooling unit comprising a header, a plurality of duct means connected with the header in parallel circuit relation, certain of said duct means being closed at the lower end, said duct means having a portion arranged to provide a freezing zone, and another portion providing a cooling zone, the material of said second-mentioned portion lying outwardly of the freezing zone in the path of the circulating medium and so constructed and arranged as to provide a shield of heat exchange material for shielding the freezing zone from the action of the circulating medium.

6. A cooling unit for mechanical refrigerators adapted to be placed in the path of the medium to be cooled thereby, said cooling unit comprising a header, a plurality of duct means connected with the header in parallel circuit relation, certain of said duct means being closed at the lower end and providing a freezing zone, and certain of said duct means providing a cooling zone, the material of the second-mentioned duct means lying outwardly of the freezing zone in the path of the circulating medium and so constructed and arranged as to provide a shield of heat exchange material for shielding the freezing zone from the action of the circulating medium.

7. A cooling unit for mechanical refrigerators adapted to be placed in the path of the medium to be cooled thereby, said cooling unit comprising a header, a plurality of duct means connected with the header in parallel circuit relation, certain of said duct means providing a freezing zone, and certain of said ducts being closed at the lower end and providing a cooling zone, the material of the second-mentioned duct means lying outwardly of the freezing zone in the path of the circulating medium and so constructed and arranged as to provide a shield of heat exchange material for shielding the freezing zone from the action of the circulating medium.

8. A cooling unit for mechanical refrigerators adapted to be placed in the path of the medium to be cooled thereby, said cooling unit comprising heat exchange means having a portion arranged to provide a freezing zone, and another portion providing a cooling zone, the material of the second-men-

tioned portion lying outwardly of the freezing zone in the path of the circulating medium and so constructed and arranged as to provide a shield of heat exchange material for shielding the freezing zone from the action of the circulating medium, said heat exchange means including a header and a plurality of ducts each connected therewith in parallel circuit relation and closed at one end.

10. 9. A cooling unit for mechanical refrigerators adapted to be placed in the path of the medium cooled thereby, said cooling unit comprising a header, opposed duct means connected with the header in parallel circuit relation and providing a freezing zone therebetween, and duct means providing a cooling zone, said second-mentioned duct means being connected with the header in circuit relation separate from one another and from the first-mentioned duct means and lying outwardly of a plurality of sides of the freezing zone in the path of circulating medium and so constructed and arranged as to provide a shield of heat exchange material for shielding the freezing zone from the action of the circulating medium.

10. 10. A cooling unit for mechanical refrigerators comprising a header for liquid refrigerant, opposed groups of ducts providing a freezing zone therebetween, said ducts being closed at their lower ends and connected at their upper ends to receive liquid refrigerant from the header and return gaseous refrigerant to the header for circulating refrigerant about the freezing zone.

11. 11. A cooling unit for mechanical refrigerators comprising a header for liquid refrigerant, a plurality of refrigerant conveying ducts, certain of said ducts being closed at their lower ends and connected at their upper ends to receive refrigerant from the header and return gaseous refrigerant to said header, said certain ducts cooperating with other of said ducts to provide a freezing zone therebetween.

In testimony whereof I hereto affix my signature.

JOHN RALPH FEHR.
